Attorney.

UNITED STATES PATENT OFFICE

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA

LOOM HARNESS

Application filed June 28, 1928. Serial No. 289,028.

My invention relates to loom harness, and it relates more particularly to means for mounting, in the heddle frames, the heddles used for controlling the warp ends for the purpose of forming successive sheds of the warp during the operation of the loom.

The principal object of my present invention is to provide improved means for mounting the heddles in the heddle frames which is particularly adaptable for close installations for weaving fine fabrics, whereby the warp ends controlled by adjacent frames will pass the eyes of the heddles more freely when the frames are reciprocated for the purpose of forming sheds, thereby minimizing, to a considerable extent, breakage of the warp ends.

Heretofore, it has been recognized by those skilled in the art that a great deal of breakage of the warp ends is caused by reason of the resistance which occurs during the reciprocation of the various heddles in the loom, at the particular instant when the warp ends controlled by one of the frames pass the warp eyes of the heddles mounted in another of the heddle frames, this occurring particularly in the weaving of fine fabrics, where the installation of the heddles in the frame is close, and where the warp is necessarily fine and easily broken.

To overcome the above mentioned difficulty, in some instances there were provided a plurality of sets of heddle frames, each set being operated in unison to control one set of the warp ends. This, however, was a more or less clumsy expedient, which led to the subsequent development of the mounting of a plurality of sets of heddles in a single frame, arranged in a plurality of separated vertical planes.

Heretofore, where two or more sets of heddles were mounted in a single frame, certain difficulties existed in connection with securing the heddle supporting rods in the frame; and furthermore, the frames were of considerable thickness, so that in some instances the requisite number could not be used in an ordinary loom.

The present invention contemplates the provision of improved means for mounting a

plurality of sets of heddles in a single frame, whereby frames of the ordinary type, such as are customarily provided for a single set of heddles, may be used, thus permitting, if desired, the employment of a portion of the standard equipment of the loom when it is required to change over to a finer count of the warp.

The nature and characteristic features of my present invention will be more readily understood from the following description, taken in connection with the accompanying drawings forming part hereof, in which:

Figure 1 is an elevational view of a heddle frame provided with improved means for mounting the heddles therein in accordance with my present invention;

Fig. 2 is an enlarged sectional view thereof, taken approximately on the line 2-2 of Fig. 1;

Fig. 3 is a similar view, taken approximately on the line 3-3 of Fig. 1;

Fig. 4 is an enlarged horizontal section, taken approximately on the line 4-4 of Fig. 1; and

Fig. 5 is a perspective view showing one end of a pair of heddle supporting rods constituting the principal novel portion of my present invention.

Referring to the drawings, the heddle frame there shown consists of the top and bottom bars 6, connected at their ends by means of the side strips 7, which are secured to the top and bottom bars at the ends thereof in any preferred manner.

Extending from end to end of the heddle frame, and arranged near the top and bottom bars, are the heddle supporting bars 8, upon which the heddles 19 are mounted. In the present instance, there are shown provided two of such bars at the top, and two at the bottom of the frame, whereby two sets of heddles 19 may be supported on said bars 8.

Near the end of each of the bars 8, the same is offset out of the plane of the main portion thereof, as at 9, and there is also provided an extending portion 10, which passes through the aperture 11 usually provided in the end strips 7 of the frame for the support of the heddle bars. The extending portion 10 of

each end of each of the heddle bars 8 may be provided with an aperture 12.

The heddle frame is provided with any preferred form of means for securing the ends of the heddle bars. As shown, the same comprises a spring member 13, one end of which is fixedly secured to the side strips 7, and the other or free end 14 of which is adapted to pass through and engage the apertures 12 in the ends of the bars 8.

It will here be noted that the apertures 12 in the adjacent ends of the bars 8 preferably register with each other, so that each of the securing devices 13 serves to engage and secure the respective adjacent ends of a pair of the heddle bars 8 (see Fig. 5).

For supporting the heddle bars intermediate their ends, and also for maintaining the same in their proper spaced relationship, whereby the heddles of one set will not foul on the other, there are provided, at suitable locations, hook members 15, each having a pair of recesses 16 in which the heddle bars 8 are located.

The hook members 15 may be secured to the top and bottom bars 6 in any preferred manner. In the drawings, they are shown as being slidably mounted on auxiliary rods 17, which are preferably of non-circular cross section, and the apertures through which the rods 17 extend are complementally shaped, so as to keep the hook members 15 from projecting beyond the faces of the frames.

The auxiliary rods 17 may be supported from the top and bottom bars 6 by means of screw eyes 18, suitably located for that purpose.

It will be seen that there is thus provided improved means for mounting a plurality of sets of heddles in a heddle frame, whereby the same may, if desired, be readily mounted in a heddle frame of standard construction.

It will also be noted that when the present invention is employed, two or more sets of heddles may be mounted in a single frame without unduly increasing the thickness thereof.

Having thus described the nature and characteristic features of my invention, what I claim as new and desire to secure by Letters Patent, is:

In a loom harness, a harness frame comprising top and bottom bars, side strips connecting said bars at their ends, a plurality of heddle supporting bars arranged at the top and bottom of the frame, said bars having their main or heddle supporting portions spaced and having their end portions offset from the respective planes of the main portions and thereby brought together and extending side by side through common apertures in the side strips of the frame, the extending ends of the heddle supporting bars having registered apertures, and means for securing the heddle supporting bars comprising

ing spring members carried by the side strips of the frame, said spring members having their ends bent over in hook-like form and simultaneously engaging the registered apertures in the extending ends of the heddle supporting bars.

In testimony whereof, I have hereunto signed my name.

JOHN JACOB KAUFMANN.
